WRITER COMPANY, OF NEW YORK, N. Y., A CORPORATION OF DELAWARE.

TYPE-WRITING MACHINE.

1,159,427.

Specification of Letters Patent.

Patented Nov. 9, 1915.

Application filed June 2, 1914. Serial No. 842,346.

To all whom it may concern:

Be it known that I, STEPHEN T. SMITH, a citizen of the United States, residing in Stamford, in the county of Fairfield and 5 State of Connecticut, have invented certain new and useful Improvements in Type-Writing Machines, of which the following is a specification.

This invention relates particularly to 10 typewriting machines of the class in which two machine frames are mounted side by side and each provided with a separate type system, in combination with a paper carriage translatable from the printing zone of 15 one type system to that of the other.

A feature of the invention is the provision of left-hand and right-hand margin gages or stops for determining the normal letter-feed travel and return travel of the 20 carriage in each printing zone; said margin gages arranged and combined with means to enable the carriage to be carried over from one printing zone to the other without interference from the gages. The left- 25 hand margin gages coöperate with line-locking mechanisms and means for operating a signal bell. A separate line-lock may be provided for each set of type keys, and release keys may be provided for releasing 30 the keys.

In carrying out the invention, the carriage is mounted to travel on guide rails, which may extend uninterruptedly across both machine frames to permit the carriage 35 to travel across both printing zones and from one zone to the other. Right-hand and left-hand margin gages may have a sliding connection with a rod extending across both machine frames, and fixed at its ends 40 in the outer ends of the machine frames. A single rack bar extending across both machine frames is mounted to rock on said fixed rod as a fulcrum. The left-hand margin gages may have a sliding connection 45 with said rack bar, and cams on said left-hand gages may be actuated by a projection on the carriage to depress said rack bar and swing forward the lower ends of arms depending from the rack bar, one of the said 50 arms operable to ring a signal bell, and each of said arms arranged to operate a line-locking device for locking a set of type keys when the end of the line of writing has been reached. The right-hand margin

gages or stops may be held in any position 55 of adjustment by a fixed rack bar extending across the machine frames parallel with said swinging rack bar. The four margin gages are arranged in alternation, the first, or right-hand gage on the right-hand machine frame determining the beginning of a line in the right-hand printing zone, the second gage determining the end of the line in the right-hand printing zone, the third determining the beginning of a line in the 65 left-hand zone, and the fourth determining the end of the line in the left-hand zone. In order to permit the carriage to be carried over from the right-hand to the left-hand printing zone, the cam on the said second 70 gage which operates the line-locking mechanism, is formed to permit the carriage to ride past it, and in order to permit the carriage to move past the said third gage, the counter-stop on the carriage which is normally intercepted by the right-hand margin gages, is in the form of a latch and may ride over the stop on said third gage. Said latch is also operable by a finger key to permit the carriage to be moved from the left- 80 hand zone to the right-hand zone.

Other features and advantages will hereinafter appear.

Certain features of the invention are usable in other connections, as for instance 85 some of the margin gage devices may be used with wide carriages in simple typewriting machines.

In the accompanying drawings, Figure 1 is a perspective view of the machine, parts 90 being broken away, and the front guide rail for the carriage removed to show the underlying parts. Fig. 2 is a detail plan view of one of the left-hand margin gages. Fig. 3 is a sectional detail showing a right-hand 95 margin gage. Fig. 4 is a sectional elevation view showing the line-locking mechanism in locking position. Fig. 5 is a sectional elevation of the machine, showing the parts in their normal position of rest. Fig. 6 is a 100 fragmentary detail view of a portion of the line-locking mechanism. Fig. 7 is a perspective view of the line-locking mechanism, the line lock for the right-hand set of keys being shown in released position. Fig. 105 8 is a detail view of a line-lock release key.

Two machine frames A and B, which may be the usual Underwood machine frames,

are mounted side by side on a common base 2, and may be secured to the base by bolts 3, and also secured together by front and rear plates or connecting blocks 4 and 5, secured by screws to the tops of the machine frames. Each frame carries a type system comprising a set of type-bars 6 fulcrumed on a rod 7 to swing upwardly and rearwardly against the front face of a roller 10 platen 8. The type-bars are operated by keys 9 on key levers 10, fulcrumed on a rod 11 and connected through bell cranks 12 to the type-bars. The platen 8 is mounted in a frame 13 shiftable to upper and lower case position in the paper carriage 14, said carriage mounted to travel on front and rear guide rails 15 and 16, which may extend uninterruptedly across both machine frames, whereby the carriage may be shifted from 20 the printing zone of one set of type-keys to that of the other set.

The carriage may be driven by a spring drum 17 journaled on one of the machine frames and connected through a band 18 to 25 the carriage. The letter-feed travel of the carriage is controlled by escapement mechanism comprising a pinion 19 running in mesh with the rack 20 on the carriage, said pinion connected to drive an escapement 30 wheel 21 controlled by escapement dogs 22 on a dog rocker 23, the latter being actuated by a universal bar 24 which is moved rearwardly by shoulders 25 on the type-bars. A universal bar and escapement mechanism is 35 provided for each set of type-keys.

The length of the line of writing is controlled by right and left-hand margin gages 26 and 27, there being a right and left-hand gage for each printing zone. The right-hand gages 26, which form stops to limit the 40 return movement of the carriage and thereby determine the point at which the line of writing commences, are slidably mounted on a rod 28, which may be fixed at its ends 45 in the outer ends of the frames A and B, and which may be supported at an intermediate point by a bracket or wing 29 on the plate 4. Adjustable collars 30 may limit the adjustment of the gages 26 toward the right. 50 Each gage 26 comprises a rearwardly extended arm 31, which has a sliding connection with a rack bar 32, provided with rack teeth 33, said rack bar being parallel with the rod 28, and also secured to the outer 55 ends of the machine frames. A holding dog 34, pivoted to the gage 26 and operated by a finger-piece 35, is formed with teeth to engage the rack teeth 33 and positively hold the gage against movement to the right from 60 any position of adjustment along the rack bar. The two gages 26 may be identical in construction, as may also the gages 27. Pointers or index fingers 36 may be attached to the gages 26 and 27, each pointer extending 65 over a scale plate 37 mounted on the

front plate or guide rail 15, (Fig. 5), said pointers indicating the letter-space positions at which the carriage will be arrested by the gages. A pointer 38 on the carriage indicates the position of the carriage relative 70 to the printing point on either printing zone. The left-hand margin gages 27 are also slidably mounted on the rod 28, and their adjustment toward the left may be limited by adjustable collars 39 on the rod 28. Each 75 gage 27 comprises a holding dog 40 (Fig. 2), pivoted at 41 and actuated by a finger-piece 42, said dogs having teeth to engage teeth 43 on a rack bar 44. The rack bar 44 is formed at its ends with arms 45 journaled 80 on the rod 28, to permit said rack to swing up and down for actuating the line locks and also for operating a signal bell.

Near the left-hand end of each machine frame is an arm 46, said arms secured to the rack bar 44 and extending downward, and each provided at its lower end with a pivoted detent 47 carrying a pin 48 to actuate an arm 49, fixed to a rock shaft 50. A locking bail for the key levers comprises a locking 90 rod 51 extending transversely beneath the key levers 10 and adapted to be swung forward to engage beneath hooks 52 on the key levers and thereby lock the latter. Said rod 51 is carried by arms 53 loose on the shaft 95 50. The rod 51 is normally held in a released position by an arm 54 fixed to the rock shaft 50, the rock shaft 50 being under the tension of a spring 55 bearing against the front face of the arm 49.

The rack bar 44 is held upward in normal position by a spring 56, and as the carriage 14 approaches its limit of travel, determined by the position of the margin gage 27, a forwardly extending arm 57 on the carriage 105 strikes a cam 58 on the gage 27 and moves the rack bar downward, thereby swinging the lower end of the depending arm 46 forward to an intermediate position. The pivoted detent 47 on the lower end of said 110 arm, as it moves forward, rides on a cam 59 on a rock arm 60, and thereby rocks the arm 60 about its pivot 63, said arm carrying the clapper 61 of a bell 62, and thus rings the bell to indicate the approach of the carriage 115 toward the end of its travel. After the bell signal is given, the writing may be continued until the arm 57 strikes a high portion 64 of the cam 58 to further depress the rack bar 44 and swing the arm 46 farther forward, thereby causing the pin 48 to swing the arm 49 forward, and rock the shaft 50. The arm 54 is thereby rocked forward, and carries with it the locking rod 51, which engages 120 beneath the hooks 52 and locks the keys. The locking rod 51 is yieldingly connected through a spring 65 to the arm 54, said connection permitting the arm 54 to swing forward independently of the locking rod if a hook 52 on a depressed key, or other ob- 125

struction, is in the path of the rod, the latter being snapped into locking position by the spring as the key moves up to normal position.

The type-keys may be temporarily released by a key 66 to permit one or more characters, usually two or three, to be written after the line lock has operated. The key 66 is provided with a cam 67 which, when the key is pushed in, strikes the arm 46 and cams it laterally, thereby carrying the pin 48 to the right and freeing the arm 49. The spring 55 then rocks said arm 49 rearwardly, and with it the locking rod 51, to release the keys. As the carriage moves forward after the keys have thus been released, the swinging rack 44 is permitted to rise to an intermediate position, owing to the high portion 64 of the cam seating in a depression 68 in the arm 57, so that the arm 46 swings rearwardly to carry the pin 48 behind the rock arm 49, the detent 47 swinging forward about its pivot to permit the pin 48 to ride over the top of the arm 49. The detent 47 drops by gravity to its normal vertical position, but is prevented from swinging beyond such position by a shoulder 47^a thereon behind the arm 46. Further movement of the carriage causes the arm 57 to again cam the rack bar 44 downward to lock the type-keys.

An abutment 69 carried by the margin gage 27 for the left-hand printing zone, and projecting into the path of the arm 57 on the carriage, forms a positive stop to finally limit the letter-feed travel of the carriage. The abutment 69 is omitted from the stop 27 in the right-hand zone to permit the carriage to be shifted from one zone to the other.

By reference to Fig. 7, it will be seen that a locking rod 51 is provided for each set of type-keys, and that a separate arm 46 is provided for operating and controlling each locking rod 51. A single bell or signal device 62 may serve for both type systems, as the swinging rack bar 44 operates to ring the bell when the cam 58 in either type zone is actuated by the carriage. A separate release key 66 is provided for each line lock, as shown in Fig. 7, so that either set of type-keys may be released independently of the other.

The return movement of the carriage is limited by a stop lug 70 on the right-hand margin gage 26, said lug lying in the path of a forwardly extending end 71 of a releasing latch 72 connected by a pivot 73 to the carriage, and operable by depressing a finger-piece 74 on the end of the latch to lift the end 71 above the stop 70. This arrangement permits the carriage to be moved from one printing zone to the other. If it is desired to move the carriage from the left-hand printing zone to the right-hand zone,

the key 74 is depressed by hand, leaving the carriage free to move past the stop 70. In moving the carriage from the frame B to the frame A, the end 71 of the stop latch may ride over the inclined face of the stop 70 without the key 74 being depressed by hand. A spring 75 returns the latch 72 to normal position. The latch 72 also permits the carriage, while in either printing zone, to be returned beyond its normal position, for the purpose of paragraphing, or writing other matter in the left-hand margin of the work-sheet.

Variations may be resorted to within the scope of the invention, and portions of the improvements may be used without others.

Having thus described my invention, I claim:

1. In a typewriting machine, the combination with sets of type-bars having separate printing zones, of a carriage mounted to travel from one printing zone to the other, a stop to limit the travel of the carriage in one printing zone, and means to release the carriage from said stop for moving the carriage to the other printing zone.

2. In a typewriting machine with separate systems of types having separate printing zones, the combination with a carriage shiftable from one zone to the other, of a margin stop to limit the return movement of the carriage while in the left-hand zone, and means to free the carriage from said stop and permit it to be shifted to the right-hand printing zone.

3. In a typewriting machine having separate printing zones, the combination with a carriage and a guide rail on which the carriage is mounted to travel in both printing zones and from one zone to the other, of right and left hand margin gages to determine the limit of travel of the carriage in both directions while in either printing zone.

4. In a typewriting machine having separate printing zones, the combination with a carriage and a guide rail on which the carriage is mounted to travel in both printing zones and from one zone to the other, of right and left hand margin gages to determine the limit of travel of the carriage in both directions while in either printing zone, said gages each adjustable in the direction of the carriage travel, and means to free the carriage from the right-hand gage of the left-hand printing zone to permit the carriage to be shifted from the left-hand zone to the right-hand printing zone.

5. In a typewriting machine, the combination with separate sets of type-bars and separate sets of type-keys for actuating said type-bars, of a paper carriage shiftable into positions to coöperate with either set of type-bars, a locking device for each set of type-keys, and means operated by the carriage when in either printing zone to actu-

- ate the said locking device for the keys of said zone.
6. In a typewriting machine, the combination with separate sets of type-keys, of a locking rod for each set of type-keys movable into and out of position to lock the keys of its set, a traveling paper carriage, a swinging rack bar, margin gages adjustable along said rack bar, cams connected to 10 said gages and adjustable therewith, means on the carriage to engage said cams and swing the rack bar, arms depending from said rack bar, and means actuated by said arms for controlling said locking rods.
- 15 7. In a typewriting machine, the combination with separate sets of type-keys, of a locking rod for each set of type keys movable into and out of position to lock the keys of its set, a traveling paper carriage, 20 a swinging rack bar, margin gages adjustable along said rack bar, cams connected to said gages and adjustable therewith, means on the carriage to engage said cams and swing the rack bar, arms depending from 25 said rack bar, means actuated by said arms for controlling said locking rods, and a signal bell operated by one of said depending arms when the carriage approaches the end of a line in either printing zone.
- 30 8. In a typewriting machine, the combination with separate keyboards, of a set of types and keys for each keyboard, a signal bell, and means to ring said bell preceding the completion of a line of writing by either 35 set of types.
9. In a typewriting machine, the combination with separate type-sets and keys for said sets, of a paper carriage movable from the printing zone of one set to the printing zone of the other set, a signal bell, and means operated by the carriage to ring said bell while the carriage is in either printing zone.
- 40 10. In a typewriting machine, the combination with separate type-sets and keys for 45 said sets, of a paper carriage movable from the printing zone of one set to the printing zone of the other set, a signal bell, means operated by the carriage to ring said bell while the carriage is in either printing zone, and line-locking mechanism to lock the set of keys in the zone in which the carriage is traveling.
- 50 11. In a typewriting machine, the combination with a plurality of sets of type-bars and keys, said sets having separate printing zones, of a paper carriage mounted to travel in either printing zone, a signal bell, and line-locking mechanism, said bell and mechanism controlled by the carriage and operated thereby at the end of a line of writing in either zone.
- 55 12. In a typewriting machine, the combination of frames placed side by side, a set of type-bars and type keys on each frame, 60 said sets having separate printing zones, a paper carriage, and line-locking mechanism for the keys of the right-hand set, said mechanism operated by the carriage, the carriage being movable past said locking mechanism to the left-hand zone.
- 65 13. In a typewriting machine, the combination of machine frames placed side by side, a set of types and type keys on each frame, said sets having separate printing zones, a carriage, a left-hand margin gage for the right-hand zone, an arm on the carriage co-operating with said gage, the carriage being shiftable to move said arm beyond the gage and bring the carriage into the left-hand printing zone.
- 70 14. In a typewriting machine, the combination of machine frames placed side by side, a set of type-bars and type keys on each frame, a swinging rack bar, a left-hand margin gage on the right-hand machine frame having a sliding connection with the rack bar and comprising a cam operable by the carriage at or near the end of the line of writing in the right-hand zone, and line-locking mechanism operated by said cam to 80 lock the right-hand set of keys, said carriage movable beyond the line-locking position into the left-hand printing zone.
- 75 15. In a typewriting machine, the combination with machine frames placed side by side, of a set of type-bars and keys on each frame, said sets having separate printing zones, a swinging rack extending across both machine frames, left-hand margin gages adjustable along said rack and each comprising a cam, an arm on the carriage to engage one of said cams at the end of a line of writing in either zone, line-locking mechanism operated by said cams to lock the keys, the cam for the right-hand set formed to permit the arm on the carriage to move past the cam for bringing the carriage into the left-hand zone, and a stop on the left-hand cam to positively limit the movement of the carriage to the left while in the left-hand zone.
- 80 16. In a typewriting machine, the combination with machine frames placed side by side, of a set of type keys and type-bars on each frame, a guide rod extending across both machine frames, right and left hand margin gages for both type sets, said gages adjustable along said rod, and a paper carriage shiftable from one printing zone past the inner gages into the other printing zone.
- 85 17. In a typewriting machine having two separate sets of types and two separate printing zones, the combination with a carriage and means to drive the carriage in letter-feed direction, of a margin stop to limit the letter-feed movement of the carriage in one printing zone, said carriage movable in letter-feed direction beyond the stopping position determined by said stop to the other printing zone.
- 90 180

18. In a typewriting machine having two separate sets of types and two separate printing zones, the combination with a carriage and means to move the carriage in 5 letter-feed direction, of two sets of type keys, a margin gage, and line-locking mechanism controlled thereby for locking one set of the keys at the end of a line of writing in one printing zone, the carriage movable beyond the line-locking position determined by the adjustment of said gage to the other printing zone.
19. In a typewriting machine, the combination with a system of type-bars and a 15 carriage, of a terminal margin gage which determines the end of the line written by said type-bars, said carriage movable freely past said gage, and a second system of type-bars operable to print on the work-sheet on 20 the carriage while the latter is in said position beyond the margin gage, said type-bar systems having separate printing zones.
20. In a typewriting machine, the combination with separate sets of type-bars and 25 keys, of a carriage shiftable into co-operative relation with either set, line-locking mechanism for locking the keys, and separate release keys for independently releasing the keys of either set.
21. A typewriting machine comprising a 30 plurality of keyboards, a plurality of alphabetical type systems having separate printing zones, one type system for each keyboard, the types of each system individually operable by their keys independently of the 35 types in the other system, a letter-feeding paper carriage adjustable from a position to co-operate with only one type system to a position for co-operating with only the other 40 type system, and margin-gage devices to cooperate with said carriage.
22. In a typewriting machine, the combination with two type systems having separate printing zones, of a letter-feeding carriage 45 movable into co-operation with either type system, and margin-gage mechanism to co-operate with said carriage to determine the beginning and ending of the line of writing when the carriage is co-operating 50 with each of said type systems.
23. In a typewriting machine, the combination with two type systems having separate printing zones, of a letter-feeding carriage 55 movable into co-operation with either type system, and margin-gage mechanism to co-operate with said carriage to determine the beginning and ending of the line of writing when the carriage is co-operating with each of said type systems; said margin-gage 60 mechanism comprising a carriage-arresting device which is releasable to permit the transit of the carriage from one type system to the other.
24. In a typewriting machine, the combination with two type systems having separate 65 printing zones, of a letter-feeding carriage movable into co-operation with either type system, and margin-gage mechanism to co-operate with said carriage to determine the beginning and ending of the line of writing when the carriage is co-operating with each of said type systems; said margin-gage mechanism comprising a carriage-arresting device which is releasable to permit the transit of the carriage from one type system to the other.
25. In a typewriting machine, the combination with two type systems having separate printing zones, of a letter-feeding carriage movable into co-operation with either type system, and margin-gage mechanism to co-operate with said carriage to determine the beginning and ending of the line of writing when the carriage is co-operating with each of said type systems; said margin-gage mechanism comprising a carriage-arresting device which is releasable to permit the transit of the carriage from one type system to the other in the direction opposite to letter-feeding direction.
26. In a typewriting machine, the combination with two type systems having separate printing zones, of a letter-feeding carriage movable into co-operation with either type system, and margin-gage mechanism to co-operate with said carriage to determine the beginning and ending of the line of writing when the carriage is co-operating with each of said type systems; said margin-gage mechanism comprising a carriage-arresting device which is releasable to permit the transit of the carriage from one type system to the other in the direction opposite to letter-feeding direction, and also comprising a carriage-arresting stop which is releasable to permit the carriage to advance in letter-feeding direction from one type system to the other.
27. In a typewriting machine, the combination with two separate systems of types having separate printing zones, of a carriage movable from one zone to the other, separate keyboards for said type systems, and line-locking mechanism for said keyboards, said line-locking mechanism under the control of said carriage.
28. In a typewriting machine, the combination with two separate systems of types having separate printing zones, of a carriage movable from one zone to the other, separate keyboards for said type systems,

and line-locking mechanism for said keyboards, said line-locking mechanism under the control of said carriage, and provided with releasing means for permitting additional key operation after the locking of the keys.

29. The combination with two type systems having separate printing zones and a carriage shiftable to position to coöperate with either type system and having letter-feeding movements when in coöperation with each type system, of margin gages for controlling the length of the written line when said carriage is coöperating with each type system; said carriage being movable from one printing zone to the other independently of said margin gages.

30. The combination with two type systems having separate printing zones and a carriage shiftable to position to coöperate with either type system and having letter-feeding movements when in coöperation with each type system, of margin gages for controlling the length of the written line when said carriage is coöperating with each type system; said carriage being movable from one printing zone to the other independently of said margin gages, and line-locking mechanism controlled by a plurality of said margin gages.

31. The combination with two type systems having separate printing zones and a carriage shiftable to position to coöperate with either type system and having letter-feeding movements when in coöperation with each type system, of margin gages for controlling the length of the written line when said carriage is coöperating with each type system; said carriage being movable from one printing zone to the other independently of said margin gages, line-locking mechanism controlled by a plurality of said margin gages, and means to release the line-locking mechanism.

45 32. The combination with two keyboards and two type systems having separate printing zones, of a carriage shiftable to position to coöperate with either type system and

having letter-feeding movements when in co-operation with each type system, margin gages for controlling the length of the written line when said carriage is coöperating with each type system; said carriage being movable from one printing zone to the other independently of said margin gages, and separate line-locking mechanisms for said keyboards, said line-locking mechanisms under the control of certain of said margin gages.

33. The combination with two type systems having separate printing zones and a carriage shiftable to position to coöperate with either type system and having letter-feeding movements when in coöperation with each type system, of margin gages for controlling the length of the written line when said carriage is coöperating with each type system; said carriage being movable from one printing zone to the other independently of said margin gages; the first of said margin gages determining the beginning of a line in the right-hand printing zone, a second gage determining the end of the line in the same zone, a third gage determining the beginning of a line in the left-hand zone, and a fourth gage determining the end of the line in the last-mentioned zone.

34. A typewriting machine comprising a plurality of keyboards, a plurality of alphabetical type systems having separate printing zones, one type system for each keyboard, the types of each system individually operable by their keys independently of the types in the other system, a letter-feeding paper carriage adjustable from a position to coöperate with only one type system to a position for coöperating with only the other type system, and margin-gage and line-locking devices to coöperate with said carriage.
